FRINGED WINDOW SHADE

Samuel J. Johnson, West Chester, Ohio, assignor
to Clopay Corporation, Cincinnati, Ohio, a cor-
poration of Maryland

Application September 27, 1939, Serial No. 296,840

2 Claims. (Cl. 156—10)

This invention is directed to window shades and has application to shades made from any of the conventional materials, such as cloth or paper. The invention is particularly concerned with the problem of providing a shade which has a decorative fringe at the lower depending margin of the shade.

There is, among a certain class of window shade purchasers, a more or less continuing demand for shades which have a decorative fringe depending from the extended margin of the shade proper. Shades of this type enjoy a particular commercial acceptance for certain types of residences or other establishments, particularly in rural sections of the country.

The conventional way of manufacturing such a shade has been to attach a pre-fabricated fringe strip to the extremity of the shade by stitching or other like means, after the shade has been otherwise completely manufactured. Fringe strips of this character usually comprise a thin strip of cloth or the like to which a fringe, which comprises a plurality of spaced tufts or tassels has been attached in some one of a number of conventional ways. A fringe strip formed in this manner provides an effective decoration for a shade, but is objectionable from the point of view of the shade manufacturer, because the initial cost of the fringe strip, plus the cost of the operation of attaching it to the shade, increases the total cost of the shade to such an extent that the shade becomes a premium item.

One of the objects of this invention has been to provide a fringed window shade in which a plurality of tufts comprising a fringe is applied directly to the margin of the shade during the course of manufacture, by hand or by the aid of simple machinery which is commercially available.

Another object of the invention has been to position and reinforce the fringe tufts in the shade margin in such a way that there is little or no possibility of the tufts pulling out, should the shade be grasped by one or several of these tufts.

Another object of the invention has been to provide a fringed shade in which it is possible to dispense with the fringe supporting strip conventional in the prior art, and associate the fringe tufts directly with the fabric of the shade margin.

Other and further objects will be apparent from a description of the drawing, in which:

Figure 1 is a perspective view of a shade constructed in accordance with the present inven-

tion, with a portion of the marginal hem cut away to expose the interior of the hem and to better illustrate the arrangement of the fringe tufts.

5 Figure 2 is a sectional view along the line 2—2, Figure 1.

Figure 3 is an enlarged view of a fragment of the cut-away portion shown in Figure 1.

10 Figure 4 is a perspective view of the lower margin of the shade, with a portion of the hem folded back to better illustrate the sequence of the method steps involved in the manufacture of the shade.

15 Referring now to the drawing for a further and more detailed description, 1, Figure 1, represents a conventional window shade made from cloth, paper, or any other like material. A roller around which the shade is adapted to be wound is shown at 2. The lower marginal edge of the shade has been folded over to form the hem, shown generally as 3. The details of this fold will be described at a subsequent point in this application. The upper margin of the hem is stitched along the line of stitching 4 to the shade proper to form a pocket for the reception of the shade reenforcing slat, shown at 5.

20 Depending from the lower marginal edge of the hem is a plurality of individual U-shaped tufts 6, forming a fringe. These tufts may each 25 comprise a group of separable or united strands of cord or string, although the exact construction of the tufts is not an element of the invention.

25 The novel features of the structure are possibly best appreciated from an examination of Figure 4, as this figure best illustrates the sequence of steps utilized in forming the construction of the invention and best emphasizes the simple yet effective nature of the improvement.

30 In Figure 4, the marginal edge 8 of the shade 1 is shown as first folded upwardly along the line 10 in a single fold. While still in folded position, the fringe is formed integrally with the shade by the expedient of forming the tuft line

35 45 9 through the hem at a point which is below the upper marginal edge 8 of the hem. This step is clearly shown at the lefthand side of Figure 4. The formation of this tuft line can be accomplished by hand, but the preferred method of 40 50 accomplishing it is by the use of a machine known as a chenille type sewing machine. This machine is conventionally used in the manufacture of chenille bed spreads and operates to thread a length of tufting cord in and out through the hem of the shade and the shade

proper, simultaneously severing the cord at spaced points on one side only (in this case, the reverse side) of the fold. The result is a plurality of individual U-shaped tufts of equal length and regularly spaced which form a fringe when the severed ends are depended from the marginal edge of the shade. The appearance of the tufts after this machine operation is best shown in Figure 3.

After the tufts have been inserted as just described, the hem is then folded upwardly a second time along the tuft line 9, and subsequently stitched along the line 4 to the shade proper.

The details of the resulting structure are clearly shown in section in Figure 2. The first hem fold portion 1, which has a terminal edge 8 rearwardly of the tuft line, acts as a reenforcing element for the fringe and strengthens the hem proper, which also performs the additional function of receiving the shade reenforcing slat 5. This slat will normally rest on the upper or doubled portion of the individual tufts, as shown in Figure 3, and tends to some extent to maintain the tufts in position. The tufts, having been threaded through two thicknesses of the shade material, are also effectively maintained in position by frictional contact against the sides of the apertures formed in the material, by the sewing operation. If desired, they can be further reenforced by pasting an adhesive strip (not shown) along the tuft line 9, Figure 4. However, if the shade material is of conventional thickness and strength, further enforcement should not be necessary.

The simplicity of the construction will be evident from the fact that the complete fringe is, in effect, formed by the single operation of forming the tuft line 9 in the manner just described, but the fringe which is formed is even more attractive in appearance than would be the case if the conventional fringe strip were simply attached to the shade, as such a strip

gives the appearance of having been simply tacked on; whereas the fringe of the invention appears as an integral element of the shade.

In the description of the shade as just set forth, the various steps of the method have also been recited. These may be summarized as the primary fold, the insertion of the tufts, the second fold along the tuft line, and the stitching of the hem. A feature of the shade is the formation of the tuft line through a double thickness of shade material, so that when the hem is folded along this line, the tufts will be effectively reenforced. This has been found to be of importance particularly in the case of paper shades. In the case of cloth shades, it is not always necessary to reenforce the tuft line, and the method can be practiced by simply forming the tuft line, folding the extended margin upwardly along the tuft line to form a hem, and then securing the hem to the body of the shade by stitching or some other suitable way.

Having fully described my invention, I desire to be limited only by the ensuing claims:

1. In a window shade having a marginal hem, a decorative fringe formed on the depending margin of said hem, said fringe comprising a series of individual sections of decorative fibre, the ends of each section being inserted through spaced apertures in the hem margin and extending downwardly therefrom, said ends being spaced equidistant from one another and being of relatively equal length.
2. In a window shade, a marginal hem for receiving a reinforcing slat, said hem being formed from at least two thicknesses of shade material, and a decorative fringe depending from said hem, said decorative fringe being formed from a plurality of individual U-shaped tufts threaded through and supported by the double thickness of the hem.

SAMUEL J. JOHNSON.
